UNITED STATES PATENT OFFICE.

RYU DIAZ WHITING, OF CHICAGO, ILLINOIS, ASSIGNOR OF ONE-HALF TO ALONZO A. WHITING, OF CHICAGO, ILLINOIS.

FURNACE.

1,258,843.

Specification of Letters Patent. Patented Mar. 12, 1918.

Application filed February 12, 1917. Serial No. 148,082.

To all whom it may concern:

Be it known that I, RUY DIAZ WHITING, a citizen of the United States, residing in the city of Chicago, county of Cook, and 5 State of Illinois, have invented certain new and useful Improvements in Furnaces, of which the following is a specification.

This invention relates to furnaces and refers more particularly to means for obtaining a more perfect combustion of the fuel 10 in the fire zone.

Among the salient objects of the invention are to introduce air or other oxygen-containing gas into the fire zone below the grate 15 in such a way as to obtain a most efficient combustion; to provide for the introduction of oxygen at atmospheric pressure and in proper quantities to the fire zone and its distribution under the grate in such a way 20 as to obtain the highest heat efficiency.

It is the purpose of the invention to provide a proper quantity of preheated air, which is delivered into the fire zone so as to cause an intimate mixture of the combustible gases, thus preventing stratification of 25 gases and obtaining the high temperatures with a consequent greater heat efficiency. Because of the reduced air supply and the reduction of velocity through the gas passages, the efficiency of combustion is increased. In practical operation, the ash pit 30 members are throttled and the damper nearly closed so as to prevent excess of draft and excess rush of air through the furnace.

The manner of introducing the air into the fire zone is important. The air is introduced into the heat zones through the air heaters located in the rear of the bridge wall or adjacent the bridge wall. These 35 retorts are preferably made of fire brick so as to retain the heat and also prevent destruction, to which a metal pipe is liable. The air is caused to pass through the retorts a sufficient distance to highly superheat the 40 air, the purpose being to introduce the air into the fire zone with as high heat as is practical.

I have further discovered that where the air is introduced through the pipe or other 50 conduit of uniform diameter that there is a pronounced tendency for an air pocket to form along the wall of the retort or pre-heater, resulting in a cold or insufficiently heated stream of air passing through the 55 center of the pipe or conduit. Such stream

of air, of course, cannot be effectively heated under such conditions. To obviate this it is very advisable that the air currents be broken up, preferably by placing obstructions in the conduit, thus preventing the 60 clinging of the heated air to the outer walls of the conduit. This is a feature of the present invention.

The advantages in distributing the air pipes under the grate instead of over the 65 grate is that the passing of the air upwardly under the grate causes it to come in contact with the latter and breaks up the air, the grate members of the fuel bed acting in effect as baffles. If the air were introduced 70 over the fuel bed, there would be a tendency for the air to stratify and escape over the bridge wall instead of being intimately mixed with the combustion gases. The features of breaking up the preheated currents 75 of air in the manner just described and the distributing of the air in unequal amounts at various parts of the fire zone are distinguishing features of the present invention. 80

Describing now the apparatus shown in the drawings for a clearer illustration of the invention,

Figure 1 is a vertical sectional view of a fire box boiler equipped with my invention, 85 parts being broken away to show interior construction and to reduce the size of the drawing.

Fig. 2 is a longitudinal sectional view taken on lines 2—2 of Fig. 1 and looking in 90 the direction of the arrows.

Fig. 3 is an enlarged top plan view of one of the air heaters and its delivery pipe.

Fig. 4 is a side elevation of the same.

Fig. 5 is a sectional view taken on lines 95 5—5 of Fig. 4, and looking in the direction of the arrows.

Fig. 6 is a sectional view taken on lines 6—6 of Fig. 3, and looking in the direction of the arrows. 100

Fig. 7 is a detailed view of the damper for controlling the inlet to the air heater.

Referring to the drawings, 1 designates as a whole the brickwork, 2 the fire box, 3 the grate, 4 the bridge wall, 5 the ash pit, 6 105 the ash door, 7 the fire box door, 8 the combustion chamber, 9 the fire tube boiler, 10 the stack, and 11 the damper controlling the stack. 12 designates one of the supports for the rear end of the boiler. At the rear of 110

the bridge wall, and at either side of the combustion chamber, at points distant from the boiler shell are the air heaters 13. Each of these air heaters is preferably formed of hollow fire brick 14, into three passages 15, 16, and 17, which communicate with each other through ports 18 and 19. Air is admitted to the lower passage 17 through suitable conduit 20, controlled by damper 21. In each of these passages or conduits of the air heater is mounted a plurality of baffle members 22, the detailed construction of which is shown more particularly in Figs. 5 and 6. These baffle members are preferably made of fire brick, asbestos rope or the like. The arrangement of these baffle members is such as to produce a swirling action of the air in each of the passages of the air heater, so that all of the air is caused to contact with the heater walls for a sufficient length of time to insure thorough heating with a minimum amount of actual obstruction to the passages.

To this end the baffle members are arranged in the form of inclined ribs projecting from the opposite walls of the passage a distance materially less than one-half the width of the passage and the ribs on one side wall of a passage are inclined reversely relative to those on the other side.

I prefer to dispose part of the ribs on opposite walls directly opposite each other, as shown in the two outside passages, Fig. 6, and part of the ribs on opposite walls staggered with relation to each other as shown in the intermediate passage. The air is delivered from the heater into a delivery pipe 23. Each of these pipes 23 is provided with air

ports 24, 25, 26, 27 and 28 respectively. It is to be particularly noted that the ports or perforations 24 to 28, decrease in size from the rear to the forward end of the pipe. There may be a number of ports of the same diameter as 24, the next of reduced diameter as 25 and so on down to the smallest ports 28. The dimensions of these ports or perforations can be varied to suit local conditions but the largest one should always be at the rear of the fire zone so that the largest amount of air is introduced at the rear for the purposes heretofore described.

The position of the air heater may be varied except that it should be at or near the rear of the bridge wall. In certain cases, one air heater with its pipe extending centrally below the grate can be used but in any event, the largest amount of air should be introduced to the fire at the rear of the fire box.

The operation of the device should be apparent from the foregoing description and need not be described in detail.

I claim as my invention:

In a furnace the combination with a fire box and combustion chamber and bridge wall therebetween, of an air heater in rear of the bridge wall comprising a plurality of passages having substantially parallel walls, baffles in said passages comprising inclined ribs projecting from the walls of said passages, the ribs on the wall of one passage being inclined reversely to those on the opposite wall of said passage, and means for conveying the air from said heater to the fire box.

RUY DIAZ WHITING.
